DES. 2224

Leonidas Macnic, of Philadelphia, Penn.
assigns to

Isaac Townsend, of the same place.

Letters Patent No. 9,124 Dated Dec. 5, 1865.

Design for a Match Safe

The schedule referred to in these letters Patent and making part of the same.

To all whom it may concern:

Be it known that I, Leonidas Macnic, of the City of Philadelphia, in the State of Pennsylvania, have invented or produced a new and original Design for a Match Safe, of which the following is a full, clear and exact description, reference being had to the accompanying drawing, making a part of this specification.

The nature of my design consists in the combined arrangement of a miniature group representing a stove and coal scuttle resting upon a shelf attached to the fire board.

In the drawing, A, is the coal scuttle; B the stove; C, the fire board; and D, the shelf.

The scuttle A, is designed to hold the matches, and the stove B, the charred splints or stems after the matches have been used; The shelf D, is designed for supporting the scuttle and stove in fixed contact with the fire board, as represented in the drawing.

Having thus fully described my invention or production

I claim, as a new and original design for a match safe, the group consisting of the scuttle A, stove B, fire board C, and shelf D, arranged and combined together as set forth and described.

Witnesses:

Benj. Morrison
Jos. Winemore.
